UNITED STATES PATENT OFFICE

JOSE MIGUEL PLA COSTA, OF BUENOS AIRES, ARGENTINA

MONTHLY ALMANAC AND THE LIKE

Application filed March 18, 1931, Serial No. 523,614, and in Argentina March 20, 1930.

This invention consists of improvements in date indicators on monthly almanacs, or similar, advertising boards etc. and is carried into effect by the use of a simple apparatus, 5 which undoubtedly offers great advantages over all other apparatus for the same object, used up to now, due its low cost and easy application, as well as other factors which will be referred to hereafter.

10 This invention is also applicable to other purposes, as will be observed in this report, as detailed in the claims hereafter.

In order to offer a clear explanation of this invention, the attached drawing illustrates 15 one form thereof.

In the drawing:

Fig. 1 shows a front view of a monthly calendar, to which the date indicator has been fixed, in accordance with the present 20 invention.

Fig. 2 shows a front view of one form of the indicator.

Fig. 3 is a vertical sectional view of the 25 device shown in Fig. 2.

In the drawing attached, the same numbers are used to indicate similar or corresponding parts.

The device of this invention, with its arrow indicator, is composed of a small ring 30 or frame (1), which may be perfectly flat, or have an added edge (2), to facilitate its handling.

This ring, or frame, may be square, round 35 or oval, or of any other intermediate shape, and in its lower part has one or more pieces (3), which may be cut out of the same piece forming the ring, or consist of pins or similar means, fixed into the lower part of the ring (1).

40 The piece or pieces (3), when cut from the same ring, are provided with an extra thickness (3') to prevent doubling when fixing them.

45 The ring (1), as well as the piece or pieces (3), whether cut from it, or fixed to piece (2) are made of tin, or of any similar material, preferentially of a flexible character, convenient for manipulation, whilst the ring 45 or frame can easily be doubled, when the

piece or pieces (3) have to be fixed in the paper.

As already remarked, the latter constitute a strengthening piece (3') which serves to procure greater rigidity.

The ring (1) also has in its lower part a small orifice, (4), through which runs a thread (not shown), united to any part of the almanac, so as to prevent it being lost.

The application of this apparatus to 60 monthly almanacs, or commercial advertising boards, is very simple, and can be done by slightly raising the leaf or sheet thereof, and perforating it with the piece or pieces (3), which are applied to the paper itself, 65 and then the apparatus remains fixed, as demonstrated in drawing 1, and in such a manner that the frame or ring (1) encircles the date or mark requiring to be emphasized.

As may be remarked, this system, when 70 compared with others of a similar nature, offers characteristical advantages to the extent that even when the indicator is fixed on any number whatever, the leaf can be raised

up in order to examine the others underneath it, without any difficulty, an operation which is very difficult in the case of all other known indicators, for the reason that in the latter case, we have to take away the indicator altogether,

75 for as a rule the leaves of the almanac are all joined together by means of apparatus which prevents us from seeing all the leaf itself; by using our invention, the whole leaf remains free, as well as visible in all its extension, and solely the date to be

80 marked has to be encircled by the marker. Moreover, in its application, this apparatus is not only sure, but of extremely easy use, and in that respect it should be observed its cheapness, for due to that circumstance, it

85 may be made of tin, or of any similar material, as well as the part used to fix it on the leaf, or made independently.

90 Although I have already said that on one of the edges I have added the piece marked (2), to make it more easily handled, at the same time the ring may be made without it, if that be more convenient for the transport of the almanac, or for other reasons.

95 My invention, as above explained, is very 100

easy to comprehend, and requires no further explanations for persons understanding its technical aspect.

It is evident that diverse modifications might be introduced in the construction and details of this apparatus, without losing its characteristics, as hereinbefore described and as set forth in the following claim.

Having already described in detail the characteristics of this invention, as well as its practical application and use, I hereby declare that I claim as my own invention, and exclusive rights and property, as follows:—

15 A calendar indicator, comprising a flat, annular ring adapted to frame the desired figure on the calendar, a triangular pin depending radially from the inner circumference of the ring, the pin being biased with
20 respect to the ring so as to be adapted to enter the paper of the calendar, and means for gripping said indicator, said means consisting of a flat, circular, radial projection from the upper circumference of the ring in
25 line with the pin, the projection being biased to provide a grip for the indicator on the side opposite to that of the point of the pin.

In testimony whereof I affix my signature.
JOSE MIGUEL PLA COSTA.
